Primary Examiner — Joseph Kukella*Assistant Examiner* — Darryl J Dardenne(57) **CLAIM**

The ornamental design for a kettle as shown and described.

DESCRIPTION

FIG. 1 is a front top perspective view showing the kettle of my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof; and,

FIG. 7 is a bottom plan view thereof.

The broken lines in the figures illustrate portions of the kettle that form no part of the claimed design.
